United States Patent Office.

BURROUGHS BEACH, OF MERIDEN, CONNECTICUT, ASSIGNOR TO
JOHN R. PEASE, OF SAME PLACE.

Letters Patent No. 95,183, dated September 28, 1869.

IMPROVED BABY-JUMPER AND ROCKER.

The Schedule referred to in these Letters Patent and making part of the same.

To all whom it may concern:

Be it known that I, BURROUGHS BEACH, of Meriden, in the county of New Haven, and State of Connecticut, have invented a new Improvement in Combined Baby-Jumper and Rocker; and I do hereby declare the following, when taken in connection with the accompanying drawings, and the letters of reference marked thereon, to be a full, clear, and exact description of the same, and which said drawings constitute part of this specification, and represent in—

Figure 1, a side view, and in

Figure 2, a top view.

This invention relates to an improvement in apparatus for the exercise and amusement of children, and consists in combining a spring-lever, to which the seat is applied, with a pair of rockers, so as to obtain the combined movement and advantages of both.

In order to the clear understanding of my invention, I will fully describe the same, as illustrated in the accompanying drawings.

A A are the rockers, similar to those commonly used for rocking-horses.

To one end an arm, B, is fixed, to which a lever, C, is pivoted, the said lever bearing upon a spring, D, the said spring resting also upon the rockers.

To the end of the lever a seat, E, is arranged, for the support of the child.

The child is placed upon the seat, and by springing up and down, causes the depression and rise of the lever, and at the same time the rocking of the whole, as denoted in broken lines, fig. 1.

For the purpose of adjusting the elevation of the seat and elasticity of the spring, I provide the arm B with several perforations, as seen in fig. 1, to either of

which the end of the lever C is attached, by passing a bolt therethrough. This would change the elevation of the seat, the spring remaining the same.

Therefore, to retain the same elevation, or nearly so, I arrange an adjusting-screw, a, forward of the arm, as seen in fig. 1, so that by the turning of the said screw inward, the lever will be depressed, or *vice versa*.

Therefore, if it is desirable for a larger child to operate on the jumper, place the bolt through a lower hole in the arm B, and depress the lever by the set-screw a. This will compress the spring so that it will support a greater weight, but if for a lighter weight, then *vice versa*.

It will be obvious that various constructions of seat for the support of the child may be applied, as a chair-seat or horse, and yet not change the general construction of apparatus.

I do not wish to be understood as claiming broadly either the rocker or spring-bar, as such, I am aware, is not new; but

What I do claim as my invention, and desire to secure by Letters Patent, is—

1. The combination of the lever C, provided with a suitable seat for the child, with the two rockers A and a spring between the two, substantially as herein set forth.

2. In combination with the above, the adjusting-arm B, with the set-screw a, as and for the purpose specified.

BURROUGHS BEACH.
